(57) **CLAIM**

I claim the ornamental design for flexible, Christmas-tree-shaped food mold, as shown and described.

DESCRIPTION

FIG. 1 is a perspective view of my new design showing interior features including rear and right side walls together with exterior features including left side and bottom end walls;

FIG. 2 is an inverted left side view thereof;

FIG. 3 is an inverted right side view thereof;

FIG. 4 is a perspective view showing exterior features including right side and bottom end walls thereof;

FIG. 5 is a rear elevational view thereof;

FIG. 6 is an inverted top end view thereof;

FIG. 7 is an inverted bottom end view thereof; and,

FIG. 8 is a front elevational view thereof.
